PAINT BRUSH AND PROCESS OF PREPAR-
ING THE SAME

Aaron Linzer, New York, N. Y.

Application March 2, 1933, Serial No. 659,411

4 Claims. (Cl. 300—21)

This invention relates to a treated paint brush and to a process for preparing a treated paint brush and has for an object to provide an improved process of preparing a paint brush and to provide an improved treated paint brush.

5 A further object of this invention is to provide a treated paint brush which need not be broken in but which is ready for immediate use without any further preparation by the pur-
chaser.

10 With the foregoing and other objects in view, as will hereinafter become apparent, this invention comprises the constructions, combinations and arrangements of parts, hereinafter set forth, disclosed and shown on the accompanying draw-
15 ing.

In the drawing,

Figure 1 is a schematic view of a paint brush receiving the first step in this improved process;

20 Figure 2 is a schematic view of a paint brush receiving a subsequent step in this process; and

Figure 3 is a schematic view of a paint brush receiving the final step in this process.

There is shown at 10 a paint brush having 25 its bristles 11 placed in a supply of raw linseed oil 12. The bristles 11 are kept in the raw linseed oil 12 over a period of twelve hours, during which time the bristles absorb the linseed oil. Once the cells of the bristles have absorbed the linseed oil, they will withstand the ravages and abuses 30 of cheap paints, substitute thinners and any other abusive materials in which they may often be used.

After the brush 10 is taken from the linseed oil 12 it is then washed in warm soapsuds 13 of 35 imported castile soap, which has a base of olive oil. After being so washed the bristles 11 are then rubbed or cleaned against sandstone, or other abrasive surface, thereby removing all sur-
40 plus linseed oil not absorbed in the cells of the bristles. This leaves the bristles clean and straight for rubbing the bristles 11 of the brush 10 on sandstone or other abrasive surface serves to "break in" the brush. That is rubbing the 45 brush on a sandstone or other abrasive surface wearing down the end of the brush to a slight taper, thereby producing a broken in new brush. Sandstones because of their roughness permit the wearing down procedure to result faster, al-
50 though it can likewise be done on an ordinary washboard or any other suitable abrasive surface. The bristles 11 are next wrapped in absorbent paper 14 which absorbent paper may be old newspaper or the like. This serves the double 55 purpose of absorbing the excess moisture in the

brush and at the same time of giving the bristles of the brush their proper form or shape.

After being wrapped in the absorbent paper 14 it is then placed in a slow heated oven 15 over a period of twenty-four hours, during which time the moisture is evaporated and a perfect prepared working tool is completed. A treated paint brush thus prepared according to the foregoing process saves the painter time in preparing such a brush for himself, eliminating the necessity of the painter "breaking in" the brush. The treated brush will in all cases have the preparedness necessary for a brush to function perfectly, thus enabling the ordinary, unskilled purchaser to have a perfect brush at his disposal on purchasing the same without being under the necessity of attempting to himself prepare the brush for use.

This process of treating the brush eliminates all dirt, dust and unwanted substances in the bristles, thus enabling the brush to function perfectly in 75 operation.

The novel features and the operation of this device will be apparent from the foregoing description. While the device has been shown and the structure described in detail, it is obvious that this is not to be considered limited to the exact form disclosed and that changes may be made therein within the scope of what is claimed without departing from the spirit of the invention.

Having thus set forth and disclosed the nature 85 of this invention, what is claimed is:

1. The process of preparing a paint brush comprising the step of causing the cells of the paint brush bristles to absorb linseed oil, washing the bristles in warm castile soap suds, cleaning the bristles against sandstone, wrapping the bristles in absorbent material to absorb moisture therefrom and shape the bristles, and exposing the bristles while so wrapped to a slow heat for a 95 period of time to evaporate the moisture and perfect the brush.

2. The process of preparing a treated paint brush comprising the step of placing the bristle end of the paint brush in raw linseed oil over a period of approximately one half a day, then washing the bristles in warm castile soap suds, then rubbing the bristles on sandstone, then wrapping the bristles in absorbent paper to shape the bristles and absorb the moisture therefrom and then exposing the bristles while so wrapped in a slow heated oven over a period of approximately a day to evaporate the moisture and perfect the brush.

3. The process of preparing a paint brush com-

prising the step of causing the cells of the paint brush bristles to absorb linseed oil, washing the bristles in warm castile soap suds, cleaning the bristles against an abrasive surface, wrapping the
5 bristles in absorbent material to absorb moisture therefrom and shape the bristles, and exposing the bristles while so wrapped to a slow heat for a period of time to evaporate the moisture and perfect the brush.

10 4. The process of preparing a treated paint brush comprising the step of placing the bristle

end of the paint brush in raw linseed oil over a period of approximately one half a day, then washing the bristles in warm castile soap suds, then rubbing the bristles on an abrasive surface, then wrapping the bristles in an absorbent material to shape the bristles and absorb the moisture therefrom and then exposing the bristles while so wrapped in a slow heated oven over a period of approximately a day to evaporate the moisture and perfect the brush.
